Primary Examiner — Samantha Q Lawrence(74) *Attorney, Agent, or Firm* — Lee & Hayes, P.C.(57) **CLAIM**

The ornamental design for a mobile stackable tower, as shown and described.

DESCRIPTION

FIG. 1 is a front, top perspective view of a mobile stackable tower;

FIG. 2 is a back, bottom perspective view thereof;

FIG. 3 is a front elevation view thereof;

FIG. 4 is a back elevation view thereof;

FIG. 5 is a left-side elevation view thereof;

FIG. 6 is a right-side elevation view thereof;

FIG. 7 is a top plan view thereof;

FIG. 8 is a bottom plan view thereof; and,

FIG. 9 is a front, top, perspective view thereof.

The broken lines shown in FIGS. 1-9 illustrate portions of the mobile stackable tower that form no part of the claimed design. The additional broken lines shown in FIG. 9 illustrate environment that forms no part of the claimed design.

1 Claim, 9 Drawing Sheets---
